DESIGN FOR A DRILL BIT

Martin Hokanson, Duluth, Minn., assignor to
Eideco, Incorporated, Duluth, Minn., a corpora-
tion of Minnesota

Application March 29, 1939, Serial No. 83,911

Term of patent 14 years

To all whom it may concern:

Be it known that I, Martin Hokanson, a citizen of the United States, residing at Duluth, in the county of St. Louis and State of Minnesota, have invented a new, original, and ornamental Design for a Drill Bit, of which the following is a specification, reference being had to the accompanying drawing, forming part thereof.

In the drawing:

Figure 1 is a side elevation of a drill bit, showing my new design.

Figure 2 is a top plan view of Figure 3.

Figure 3 is an elevation at right angles to
Figure 1.

Figure 4 is a bottom plan view of Figure 1.

I claim:

The ornamental design for a drill bit, as
shown.

MARTIN HOKANSON.
